UNITED STATES PATENT OFFICE.

STERLING W. WARNER, OF WESTFIELD, NEW JERSEY, ASSIGNOR TO THE AEOLIAN COMPANY, A CORPORATION OF CONNECTICUT.

TRACKING DEVICE FOR MUSIC SHEETS AND THE LIKE.

Application filed October 9, 1920, Serial No. 415,847. Renewed May 6, 1924.

To all whom it may concern:

Be it known that I, STERLING W. WARNER, a citizen of the United States, residing at Westfield, in the county of Union, New Jersey, have invented certain new and useful Improvements in Tracking Devices for Music-Sheets and the like, of which the following is a specification.

My present invention relates to improvements in tracking devices for music-sheets and the like.

In the usual tracking device, the wandering of the sheet out of track varies the condition of a control port or ports to open or close same more or less in order to induce a corrective device to operate to correct the wandering of the sheet.

The main defect of such devices is that the sheet has to wander too far out of track before the control port is sufficiently affected to induce the corrective device to operate. This defect is largely due to the inertia of the corrective device requiring a relatively large amount of power to set said device into operation. This permits the sheet to wander too far out of track before the correction is made.

My present invention overcomes this defect by the ways and means shown, described and claimed in the annexed drawings and specifications.

In the drawings, which show only one of the preferred embodiments my invention is adapted to take in connection with a player-piano,—Fig. 1 is a front elevation of my improved tracking device and of the immediately related parts of the player-piano; Fig. 2 is a vertical sectional enlarged view through the motor pneumatics that correct the wandering of the sheet; Fig. 3 is a view on the line 3—3 in Fig. 2 looking in the direction of the arrows; Fig. 4 is a vertical sectional enlarged view through a control device located between the sheet-controlled port or ports and the aforesaid motor pneumatics; and Fig. 5 is a view on the line 5—5 in Fig. 4 looking in the direction of the arrows.

Describing now the devices of the drawings,—1 is the music-roll box of a player-piano or the like; 2 is the tracker-bar; 3 is a music-roll and sheet; 4 and 5 are the spindles for supporting the music-roll, the latter being the live or driving spindle secured to the end of the shaft 6; 7 is the take-up

spool, provided with the gear-wheel 8 and supported on the trunnions 9—9.

10 is the suction-motor for driving the sheet; whose crank shaft 11 supports a sprocket 12 which through a chain 13 drives another sprocket 14 on a shaft 15 on whose end within the music-roll box 1 is a pinion 16, said shaft 15 being supported to be movable endwise to carry said pinion 16 into mesh with said gear-wheel 8 so that the motor 10 then drives the take-up spool and thereby draws the sheet downwardly across the tracker-bar to play it, or vice versa permits said pinion 16 to be drawn to the right in Fig. 1 out of mesh.

To effect rewinding of the sheet back onto the music-roll, 17 is a sprocket loose on the shaft 15, connected by a chain 18 with a fixed sprocket 19 on the music-roll driving spindle 6. The loose sprocket 17 has a clutch-pin 20 adapted to be engaged by the coacting pin 21 of a clutch sleeve 22 slidably fixed between limits on the shaft 15 by a spline 23. 24 is a lever pivotally supported at 25 whose upper-end is located in the annular groove in the clutch sleeve 22. When this lever is swung from its position in Fig. 1 toward the right, it carries the shaft 15 and pinion 16 out of engagement with the take-up spool and at the same time carries the pin 21 of the clutch sleeve 22 into rotary driving engagement with the pin 20 on the sprocket 17, whereby the motor 10 then drives the music-roll spindle 6 and rewinds the sheet onto the music-roll.

The music-roll is spring-pressed to the right by a compression-spring 26 acting against the endwise movable head 4 of the left-hand supporting-spindle for the music-roll.

The music-roll is adjustable to the left against the action of said spring 26 by the cam 27 acting against the end of the music-roll driving spindle 6 which for this purpose is movable endwise in its bearings. Said cam 27 is part of an elbow-lever 28 pivotally supported at 29.

The upper end of this elbow-lever 28 is operatively connected to the pneumatic means shown at the left in Fig. 1 by a member consisting of two rods 30—31 adjustably connected by a turn-buckle 32 engaging the oppositely screw-threaded ends of said rods.

33—34 are control-ports consisting of ducts in the tracker-bar at the edges of the

music-sheet. These control-ports 33 and 34 are connected by tubes 35 respectively with interconnected balanced pneumatics 36 and 37 mounted on the stationary block 38 supported by the bracket 39 upon the music-roll box. The movable boards of the bellows are connected by the link 40.

Both of said bellows are normally on suction applied through the tube 41 by way of the bleeds 42-42 in a passage in the block 38.

43-44 are valves mounted on stems screw-threaded for adjustment through lugs on the movable boards of said pneumatics.

15 Said valves 43-44 coact with a second pair of control-ports 45-46, being the ends of nipples supported by the block 38, and are connected by tubes 47 respectively with two large, opposed motor pneumatics 48-49.

20 The movable boards of these pneumatics are interconnected by a link 50, and this in turn is pivotally connected with the previously described cam-operating rod 30.

These motor pneumatics 48-49 are 25 mounted on a block 51 supported by brackets from the side of the music-roll box. Both of said pneumatics are normally on suction applied through the tube 52 by way of the bleeds 53-53 in a passage in 30 said block 51.

The other pneumatics 36-37 have purposely a small capacity (as compared with the motor pneumatics 48-49) so that they are sensitively balanced and so that their 35 balance is upset by even a slight differential change in the pneumatic condition of the tracker control ports.

The operation is as follows:—Fig. 1 shows the sheet in accurate tracking relationship to the tracker-bar and all the other parts positioned accordingly. The pneumatics 36 and 37 are equally balanced against each other because the same amount of suction is being applied to them through the tube 41 and the bleeds 42; also because said suction is being weakened to the same extend by the atmospheric air sucked into the pneumatics through the equally open control ports 33-34. Therefore, the pneumatics assume the position shown in Fig. 1 with their valves 43-44 equally spaced from their respective ports 45-46. In other words, the equally open pneumatic condition of the control ports 33-34 is duplicated at the second pair of control ports 45-46. This causes the motor pneumatics 48-49 also to be equally balanced against each other so that through the rod 30, the cam 27 is positioned as shown holding the music-roll against the pressure of the spring 26 in the central position shown corresponding to the accurate tracking position of the sheet.

Should now the sheet begin to wander, 65 for instance, to the left, it will open port

34 more than port 33; consequently, more atmospheric air will be entering pneumatic 37 than 36, and their sensitive balance will be instantly upset, the pneumatic 36 contracting and the pneumatic 37 expanding.

The result will be that the valve 43 will be moved still farther away from the port 45 in Fig. 1, whereas the valve 44 will close or substantially close the port 46, whereby the port 45 will be admitting considerable air 75 into the power pneumatic 48, whereas the port 46 will be admitting practically none into the other motor pneumatic 49. Therefore, the much greater exhaust in 49 will cause this pneumatic to overpower the pneumatic 48, and will push the rod 30 to the right and rock the cam 27 upwardly, whereby a lower part of the cam then bears against the spindle 6 so that the spring 26 now pushes the music-roll and music-sheet 85 to the right until the sheet is again symmetrically located over the first control ports 33-34, by which time all of the parts are restored to their original positions in Fig. 1 because now the pneumatic condition 90 of both ports 33-34 is equalized, which in turn automatically equalizes the pneumatic condition of the second pair of control ports 45-46, which in turn equalize the motor pneumatics 48-49.

Similarly any right hand wandering of the sheet is instantly corrected by a reverse operation of the parts to that just described.

The device is unusually effective due to 100 the tracker ports 33-34 being used to control the motor pneumatics 49-48 not directly but through an intermediate balanced control means which is sensitive to any difference in the pneumatic condition of the 105 tracker-ports.

When the tracker ports are used directly to control the motor pneumatics, these latter are necessarily so large and have so much inertia to overcome to shift the music-roll, that the sheet must wander relatively far out of track before there is enough difference created in the pneumatic condition of the respective tracker ports to induce the large motor pneumatics to operate 115 to restore the sheet into track.

The interposition of the small, sensitively balanced pneumatics 37-36 doing no work except to shift the valves 43-44 overcomes this defect, so that they respond to 120 the slightest differential change in the pneumatic condition of the tracker ports; and instantly reproduce exaggerated differential changes in the pneumatic condition of the other control-ports 43-44. This so greatly magnifies the differential suction in the respective motor pneumatics that in spite of their large size and inertia, they readily operate without the sheet wandering farther out of track.

The device has been shown and described as operating on suction but it would be an obvious equivalent to introduce the obvious changes well-known to those skilled in this art to make the device operate on pressure. Also, obviously, other changes can be made in the above at present preferred embodiment of my invention without departing from the essence thereof and which will still 10 come within the spirit of said invention and the annexed claims.

What I claim is:

1. The combination in a tracking device of two control-ports appurtenant to the 15 tracker-bar arranged respectively to have their pneumatic conditions oppositely varied by wandering of the sheet; interconnected balanced pneumatics, both operative on suction and severally connected with the two 20 control-ports; additional control-port and valve means operated by said balanced pneumatics; and pneumatic motor means adapted to be connected direct to the atmosphere through said additional control- 25 port means to be governed thereby and operatively arranged to correct the wandering of the sheet.

2. The combination in a tracking device of two control-ports appurtenant to the 30 tracker-bar arranged respectively to have their pneumatic conditions oppositely varied by wandering of the sheet; interconnected balanced pneumatics, always subjected to suction and severally connected with the 35 two control-ports; two additional control-ports and valves for same operated by said

balanced pneumatics; and interconnected motor-pneumatics, both operative on suction and severally connected with the two additional control-ports to be governed thereby, 40 said motor pneumatics being operatively arranged to correct the wandering of the sheet.

3. The combination in a tracking device of two control-ports appurtenant to the 45 tracker-bar arranged respectively to have their pneumatic conditions oppositely varied by wandering of the sheet; balanced pneumatic means maintained under suction and operatively connected with said control- 50 ports and arranged to have its balance upset by a differential change in the pneumatic condition of said ports; and motor means governed by said balanced pneumatic means and operatively arranged to correct the 55 wandering of the sheet.

4. The combination in a tracking device of a control-port appurtenant to the tracker-bar arranged to have its pneumatic condition varied by the wandering of the sheet; 60 balanced pneumatic means subjected to continuous suction and operatively connected with said control-port and arranged to have its balance upset by a variation in the pneumatic condition of said port; and motor 65 means governed by said balanced pneumatic means and operatively arranged to correct the wandering of the sheet.

In testimony whereof, I have signed my name to this specification this sixth day of 70 October 1920.

STERLING W. WARNER.
